ABSTRACT

In an electrohydrodynamic generator, a collector extension covers the collector/injector interspace region and prevents radial dispersion of charge carriers. The collector extension is tubular leaving the main body of the collector and opens into a wide mouth at the top of the injector assembly. The mouth is even with or extends past the top of the injector assembly.

FIG. 7

ELECTROHYDRODYNAMIC GENERATOR WITH COLLECTOR EXTENSION

BACKGROUND OF THE INVENTION

1. Field of the Invention

The present invention relates to improved flowing liquid electrostatic generators.

2. Description of the Prior Art

Recent developments have indicated that flowing liquid electrostatic generators, referred to as electrohydrodynamic (EHD) devices, can meet the need for electrostatic devices capable of producing voltages within the range 500 kv. to 2 mv. Such units could be used for E.H.V. electron microscopes and for use in semiconductor or integrated circuit ion implantation service.

The operation of flowing liquid electrohydrodynamic (EHD) devices is based upon the fact that it has been found to be possible to inject significant currents into dielectric liquids, e.g., hexane, in a nondestructive manner by using an injection system which includes field-emitting electrodes. In its most basic form, the injection system consists of a razor blade, serving as the injecting or emitting electrode, mounted perpendicularly to a flat wire mesh grid, serving as a positively biased counter electrode. Application of a voltage of about 10 kv. to this diode provides, due to the intense field emission, a negative space-charge sheath around the razor edge. The electrons which are emitted from the metal surface of the razor are trapped by liquid molecules in the dielectric to form negative low mobility charge carriers. These charge carriers move towards the grid or counter electrode under the action of the electric field.

Collisions between charge carriers and neutral molecules in the bulk liquid result in momentum transfer. Close to the grid, momentum transfer from the mechanically driven bulk liquid to the charge carriers sweeps some of the charge carriers beyond the grid wires and into a field-free region beyond the grid.

A simple EHD generator consists of a charge injector to produce charge carriers, a means for moving the liquid to enable the charge carriers to be driven into a field-free region, and a means for stripping the charge from the liquid.

FIG. 1 of the drawings illustrates a typical prior art EHD generator in simplified form. With reference to FIG. 1, the razor blades or injector or emitter electrodes are denoted by numeral 102, a flat wire mesh grid or counter electrode by numeral 104, the collector by numeral 106, holding brackets by numeral 112, a conduit for liquid flow by numeral 114, and the grid holder by numeral 116.

In such a system, the flowing liquid is returned to the emitter 102 after passage through the collector 106 by a return conduit not shown in FIG. 1. The return conduit may be formed of glass or a plastic, such as unplasticized polyvinyl chloride. A circulating pump to mechanically drive the liquid through the system is usually incorporated in the closed loop. For hexane, fluid velocities in the injector have been as high as 0.5 m./s. High fluid velocities significantly enhance the injector current. This is believed to be the result of space-charge removal from the emitting edges of the injecting device (razor blades).

Each of the three razor blade emitters 102 typically has an edge length of 12 mm. and a tip radius of approximately 1,250 A. With a suitable potential difference between the emitters 102 and the grid 104, field-controlled emission occurs into the flowing liquid dielectric. Rapid field divergence away from the emitter edge insures that liquid ionization and deterioration is small. Because of the small radius of the razor blade tips, an applied voltage of only a few kv. results in intense electric field and copious electron emission. This provides the high density of negative charge carriers in the dielectric liquid, and the region about the injector can be considered a quasivirtual cathode. The space charge, due to the negative charge carriers in this region, reduces the field at the razor blade edges so that in the steady state emission is reduced to that level required to offset

the charge loss by conduction from the virtual cathode region. Emitter 102-grid 104 spacings in the prior art have typically been 1-2 mm., providing an emitter field of approximately 10^7 to 10^8 v.cm.⁻¹.

5 The magnitude of current resulting from the application of an adequate voltage between the emitters 102 and the grid 104 is basically proportional to the product of the number of emitters and the total carrier velocity. If adequate separation between the razor blade emitters 102 is provided so that each 10 emitter can operate in a space-charge limited mode, multiple blade arrays in excess of three can be used to provide substantial injector currents. For instance, the prior art obtained a maximum injector current of 550A. utilizing 43 blades with a tip-grid spacing of 1 mm. and an applied voltage of 9.5 kv.

15 The prior art has also used multiple-tipped corona emitters and sharp line emitters. For the latter system, ionization was increased by using an easily dissociable additive in N-octane. Chemical degradation of the liquid was encountered in such systems.

20 The grid 104 may consist of a fine mesh grid of 30 lines per inch and the collector may be cylindrical brass plug. The grid is required to establish the field necessary to create negatively charged carriers in the liquid and is positively biased with respect to the emitter. The meshed shape of the grid and the fast flowing liquid help to carry the charge carriers past the grid to the collector where they are scavenged or collected.

25 Instead of using separate assemblies for emitter and grid electrodes, it is also known to use a single injector assembly which includes a centrally placed cylindrically shaped counter electrode (acting similar to the grid) and a plurality of emitters or injecting electrodes (razor blades) placed circumferentially around the counter electrode, with the liquid flow occurring through the injector assembly to sweep away the charge carriers created thereby.

30 Once an EHD generator, as described, is in operation, the potential on the collector builds up relative to the injection system. The associated electric field exerts a repelling effect

35 on further charge carriers moving towards the collector. At 40 some point, this repelling force on the charge carriers reaches a degree where the charge carriers become stalled between the injector and the collector due to the collector repelling field nearly balancing out the momentum transfer effect of the flowing liquid. At this point, where axial carrier motion becomes greatly reduced, the charge carriers which are essentially stationary are prone to radial diffusion as a result of their 45 mutually repulsive field. This effect results in serious charging of any insulating walls bounding the conversion space. This can lead to disruptive flashover to any grounded surface. 50 Furthermore, device efficiency is seriously lowered since charge carriers are effectively lost from the collector. The present invention solves both of these problems.

55 One solution to the problem of radial charge carrier dispersion is disclosed and claimed in the copending patent application of P. E. Secker, entitled "Improved Flowing Liquid Electrostatic Generators," filed Mar. 23, 1970, and having Ser. No. 21,742. The solution described therein includes the creation of a sheath of uncharged liquid surrounding and traveling parallel to the charged liquid in the injector/collector inter-space region. The injector assembly contains surrounding inlet/outlet ports which allow a part of the liquid to pass therethrough unaffected by the injector charge emission.

60 As will be appreciated by one skilled in the art, the theory and practice of EHD generators is well documented, and the applicants accordingly wish to incorporate, by reference, the following publications which discuss the operation of EHD generators:

SUMMARY OF THE INVENTION

Substantially all radial charge carrier dispersion in the injector/collector interspace region is eliminated by the present invention.

A collector extension down to and partially surrounding the injector assembly results in an electric field in the region of the injector assembly having lines of force directed inwardly. The lines of force tend to "push" back the charge carriers which would otherwise be radially dispersed to the outer walls of the generator conduit. The collector extension enclosing the injector/collector interspace is bell shaped or bottle shaped to result in the desired lines of force. The injector assembly is mounted on a platform which is movable up or down to vary the relative position of the injector assembly and the mouth of the collector extension to achieve optimum voltage generation.

BRIEF DESCRIPTION OF THE DRAWINGS

FIG. 1 is a cross-sectional view of a prior art EHD generator;

FIG. 2 is a cross-sectional view of a preferred embodiment of the present invention;

FIG. 3 is a top view of the preferred injector assembly used in connection with the embodiment shown in FIG. 2;

FIG. 4 is a cross-sectional view of the injector assembly of FIG. 3 taken along lines 4-4 of FIG. 3;

FIG. 5 is a front view of a blade holder assembly which forms a part of the injector assembly of FIG. 3;

FIG. 6 is a perspective view of the blade holder assembly; and

FIG. 7 is a schematic diagram of a part of the injector/collector assemblies and illustrates the lines of force which are generated.

DETAILED DESCRIPTION OF THE PREFERRED EMBODIMENT

The broad theory of EHD generators has been heretofore outlined in the description of the prior art. The following discussion is offered to set the context of the present invention in systems which have proven most efficient. It will be appreciated by one skilled in the art that the practice of the present invention can find application in systems as the prior art has utilized, and in systems which will vary from those described in the specification. In the preferred embodiment of this invention, hexane is utilized as the liquid dielectric material. Other materials, such as freon, etc., could be used. It is of primary importance that the following criteria be met for the liquid dielectric, rather than any one special dielectric be selected. Specifically, the dielectric must have good insulating properties. Hexane, when purified, has a dielectric strength exceeding 10^6 v./cm. The liquid dielectric must further have a low negative carrier mobility, a low viscosity and preferably be nonflammable. Typical viscosity values are equal to or less than 0.5 centistokes. Any liquid with the above criteria could be used in the EHD generator of this invention.

The negative charge carrier mobility for hexane is only 1.5×10^{-4} cm.²/v./sec. Negative charge carrier mobilities of this magnitude serve excellently in an EHD generator. With typical injector designs, the unipolar charge current density in the conversion space with hexane will be approximately 1.5 μ A./cm.². It is possible that the prior art dielectrics, such as gaseous, gaseous-solid systems and the like could be used in this present invention. For instance, the prior art utilized dust particles, aerosols, glass beads, water droplets in a gas, and metal or gas bubbles in the dielectric liquid. Problems were encountered with the use of such carriers, such as accumulation of the charge carriers in regions of high electric field resulting in electrical breakdown.

As illustrated in FIG. 2, a preferred embodiment of the EHD machine comprises a generator portion 40, conduits 10, 20 and 21 for carrying liquid to and from the generator portion 40, a heat exchanger 14 having inlet tube 16 for carrying water, mechanical pump 22, and bellows 12 and 24.

The heat exchanger 14 is included to control the temperature of the dielectric liquid, preferably purified hexane, which flows through the system. It has been found that by increasing the temperature of the dielectric by approximately 10° C. a pressure of 7-8 p.s.i. develops in the system and inhibits bubble formation in those areas in which drastic changes in cross sectional flow area occur. A further advantage of operation at elevated temperature is that moisture condensation on various external parts of the system is minimized.

15 The mechanical pump 22 sweeps the liquid out of the collector region of the generator portion 40 and into the injector area of the generator portion 40. The flow of the liquid dielectric is in the direction indicated by arrows 41, 42, 44, 46, 48 and 50. The bellows 12 and 24, which may be Teflon bellows, are provided to isolate the generator portion 40 from any vibration of mechanical pump 22.

The generator portion 40 includes an injector assembly 32 mounted on an elevator mechanism 30 for raising or lowering the injector assembly. The elevator mechanism is shown only by way of example as including a motor 31 and gear means 33. The elevator mechanism should include openings therethrough for passage of the uncharged liquid dielectric in the direction of arrow 48. Other than fulfilling the latter requirement, just about any elevator mechanism would be suitable.

25 The generator portion 40 also includes a collector electrode assembly comprising a main portion 34, an outlet portion 38 and a collector extension 36 having a mouth which extends a least level with the top of the injector assembly 32 and preferably slightly below.

30 As is known in the prior art, the liquid dielectric passes into the injector assembly 32, emerging as a charged liquid dielectric. The charged liquid dielectric passes into, through, and out of the collector assembly emerging again as an uncharged dielectric liquid. The collection or scavenging of charges by the collector is enhanced by increasing the ratio of surface area/volume of collector. Increased scavenging has been accomplished by cutting up old automobile radiators and stuffing them into the hollow cylindrical portion of the collector 34, thereby greatly increasing the surface area of the collector electrode. The metal used to make the collector should preferably be easily cleaned and relatively slow to oxidize. Copper has been found suitable although not the only metal suitable.

35 The active portion of the generator is held away from the insulating walls 26 by means of insulating platform 43. Electrical connections, not shown, are made in a known manner to the emitter and counter electrodes of the injector assembly 32 and the collector electrode.

40 The manner in which the invention operates to prevent radial charge dispersion can best be understood by referring to FIG. 7 wherein the lines of force, due to the electrical field between the collector extension 702 and the injector assembly 700, are designated by the numeral 704. The liquid flowing out of the injector is shown at 706 and the insulating walls of the generator portion are shown at 708.

45 As is well known, in flowing liquid electrostatic generators, momentum transfer from the liquid molecules, as the liquid passes through injector assembly 700, to the unipolar charge carriers, generated by the injector assembly, causes the charge carriers to migrate from the injector assembly 700 to the collector electrode. Consequently, the charge is moving counter to the collector/injector electric field. Near the maximum output voltage the carriers are quasistalled between injector and collector and previously would undergo radial diffusion as a result of their mutual repulsive field. Such behavior gives rise to the loss of charge carriers from the collector and also can cause charging up of the insulating sidewalls and subsequent flashover to ground.

By suitably shaping the entry port (collector extension 702) of the collector electrode as illustrated in FIGS. 7 and 2, a collector/injector electric field distribution can be established which both aids axial carrier collimation and positively prevents all carrier escape from the injector/collector region. The electric field set up by the potential difference between the collector and injector has an inward radial component to counteract the mutual repulsion field between the carriers. Should a carrier diffuse from the central flowing core of liquid, it moves into a region where the liquid is almost stationary and the electric field returns the carrier to the injector. The injector/collector system thus constitutes an "electrostatic bottle" from which carriers cannot escape to set up undesirable insulation charging effects.

A preferred embodiment of a novel injector assembly which is suitable for use with the present invention is illustrated in FIGS. 3 through 6. The assembly is cylindrically shaped and includes a counter electrode up of center post 300 and surrounding rings 314 and 318, together with an emitter electrode comprising 21 razor blades 310 having a total of 42 emitting edges. It will be noted that the novel injector assembly illustrated herein is designed to utilize both edges of each razor blade as emitting or injecting surfaces, whereas the injector assembly described in the copending application mentioned above uses only a single edge of each blade.

The assembly comprises four concentric cylindrical rings 312, 314, 316 and 318. Center post 300 as well as rings 314 and 318, may be constructed of stainless steel and rings 312 and 316 may be constructed of an insulating material, preferably polytetrafluoroethylene (PTFE). All four concentric rings are structurally held together and to center post 300 by means of upper and lower spider members 320 and 322, respectively, which may also be constructed of stainless steel. Spider 320 is flat and is held to center post 300 and to all of the rings by means of screws 324. Spider member 322 comprises three separate rectangular plates welded to rings 314 and 318 and to center post 300. A side view of spider 322 is shown in FIG. 4.

Each blade 310 is held by a blade holder 330 which may be constructed of PTFE or other easily machinable plastic. There are 21 blade holders shown in the embodiment and they are evenly spaced around the periphery of rings 312 and 316. Each blade holder is fitted into slots made therefor in rings 312 and 316. The slots are illustrated by the dotted line 500 shown in FIG. 5. As shown in FIGS. 5 and 6, each blade holder consists of two like parts 600 and 602 which are attached to the insulating rings by means of screws. The inner faces 604

and 606 hold the blade in place and are held together also by means of screws.

It can be appreciated, from the particular construction shown, that each edge is near either the center post 300 on one of the rings 314 and 318, and that since the latter three metal members are connected together, the rings 314 and 318, as well as the center post 300, serve as the counter electrode.

It will further be appreciated by one skilled in the art that although razor blades have been delineated as the emitters per se, any comparable means can be used so long as each emitter operates in the field-emitting mode and no ionization of the liquid occurs.

What is claimed is:

15. In an EHD generator of the type having a injector assembly for injecting charge carriers into a flowing liquid dielectric, a collector for scavenging the charges from said flowing liquid and means for recirculating said liquid through the injector assembly and said collector, the improvement comprising:
an electrically conductive extension electrically in contact with said collector and extending from said collector to said injector assembly without touching said injector assembly,
20 said extension being attached to said collector and forming a part thereof,
said extension being shaped to provide electric field lines of force which, in the area near the output side of the injector, are directed radially inward when said collector and injector assemblies are provided with potentials in the conventional manner for operating an EHD generator,
25 and wherein said extension is a hollow tubular member which is flared outwardly adjacent said injector assembly to define a mouth with a cross-sectional area greater than the cross-sectional area of the output side of said emitter.
30. The invention as claimed in claim 1 wherein the mouth of said extension is at least even with the output side of said injector assembly so that there is no interspace region between injector assembly and collector which is not surrounded by said extension.
35. The invention as claimed in claim 2 further comprising means for adjusting the relative positions of said collector mouth and said injector assembly output side.
40. The invention as claimed in claim 3 wherein said adjusting means comprises an elevator mechanism attached to said injector assembly.
